Primary Examiner — R. Johnson*(74) Attorney, Agent, or Firm* — Knobbe, Martens, Olson & Bear, LLP(57) **CLAIM**

The ornamental design for the guitar, as shown and described.

DESCRIPTION

FIG. 1 is a perspective view of a guitar showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof;

The broken lines in the views depict features of the guitar which form no part of the claimed design.

1 Claim, 7 Drawing Sheets(56)
